(57) CLAIM

The ornamental design for a prosthetic liner support hook, as shown and described.

DESCRIPTION

FIG. 1 is a perspective view of a prosthetic liner support hook, showing my new design;

FIG. 2 is a side view thereof, the opposite side view being a mirror image;

FIG. 3 is a front view thereof;

FIG. 4 is a rear view thereof;

FIG. 5 is a bottom view thereof;

FIG. 6 is a top view thereof;

FIG. 7 is a perspective view of a second embodiment of a prosthetic liner support hook showing my new design;

FIG. 8 is a side view of the second embodiment, the opposite side view being a mirror image;

FIG. 9 is a front view of the second embodiment;

FIG. 10 is a rear view of the second embodiment;

FIG. 11 is a bottom view of the second embodiment; and, FIG. 12 is a top view of the second embodiment.
